DESIGN FOR A TOOL AND IMPLEMENT
HOLDER

Alfred W. Wickesberg and Edward C. Klotz, Jr.,
Milwaukee, Wis.; said Klotz assignor to said
Wickesberg

Application November 28, 1945, Serial No. 124,150

Term of patent 7 years

(Cl. D44—29)

To all whom it may concern:

Be it known that we, Alfred W. Wickesberg and Edward C. Klotz, Jr., citizens of the United States, residing at Milwaukee, in the county of Milwaukee and State of Wisconsin, have invented a new, original, and ornamental Design for a Tool and Implement Holder, of which the following is a specification, reference being had to the accompanying drawing, forming part thereof.

Figure 1 is a perspective view of the holder showing our new design;

Figure 2 is a horizontal sectional view of the holder taken on the line 2—2 in Figure 4;

Figure 3 is a rear view of the holder; and

Figure 4 is a front view of the holder.

We claim:

The ornamental design for a tool and implement holder, as shown.

ALFRED W. WICKESBERG.
EDWARD C. KLOTZ, JR.
